8960

8960-

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S LONG COAT.

SPECIFICATION forming part of Design No. 14,477, dated December 11, 1883.

Application filed October 27, 1883. Term of patent 3½ years.

To all whom it may concern:

Be it known that I, CATHERINE O'HARA, of the city, county, and State of New York, have invented and produced a new and original Design for a Pattern of a Lady's Long Coat, with Vest, (numbered 8,960;) and I do hereby declare that the engraved prints accompanying this specification convey to any one accustomed to using paper patterns a clear understanding of how a garment made up by the pattern will appear.

The design combines close-fitting vest-fronts that are turned back in lapels above the closing, cut slightly away below the closing, and overlapped at the sides by shorter close-fitting side fronts, a long close-fitting back with a lap

below the lower end of its center seam, and side skirts that lengthen the sides of the coat evenly with the back and have pocket-laps falling over their tops, a standing collar being added to the back and vest portions, and a rolling collar to the back and side fronts, coat-sleeves being also added.

What I claim as my invention, and desire to secure by Letters Patent, is—

The design for a lady's long coat with vest, as shown in the engraved prints accompanying this specification.

CATHERINE O'HARA.

Witnesses:

MARCELLUS CARLETON SHATTUCK,
ALFRED FRANCIS.
